(**) Term: **14 Years**

(21) Appl. No.: **29/364,544**

(22) Filed: **Jun. 24, 2010**

DESCRIPTION

(63) Continuation-in-part of application No. 11/965,881, filed on Dec. 28, 2007, now abandoned.

FIG. 1 is a perspective top view of the clip for connection to a stab terminal of an electrical buss, in accordance with our new design;

(51) **LOC (9) Cl.** 08-05

FIG. 2 is a top view of the clip for connection to a stab terminal of an electrical buss, in accordance with our new design;

(52) **U.S. Cl.** D8/356

FIG. 3 is a left side view of the clip for connection to a stab terminal of an electrical buss, in accordance with our new design;

(58) **Field of Classification Search** D8/356,

FIG. 4 is a front view of the clip for connection to a stab terminal of an electrical buss, in accordance with our new design;

D8/349, 353, 354, 367, 371, 382, 499, 373; D13/133; 439/436, 439, 883, 860, 441, 438, 439/246, 249, 76.2, 668, 857, 736, 225, 422, 439/492, 741, 861, 660; 200/284, 238, 237; 174/650, 1, 66

FIG. 5 is a rear view of the clip for connection to a stab terminal of an electrical buss, in accordance with our new design;

See application file for complete search history.

FIG. 6 is a bottom view of the clip for connection to a stab terminal of an electrical buss, in accordance with our new design; and,

(56) **References Cited**

FIG. 7 is a right side view of the clip for connection to a stab terminal of an electrical buss, in accordance with our new design.

U.S. PATENT DOCUMENTS

The broken lines identify the subject matter that forms no part of the claimed design.
